HOLDER FOR A PORTABLE RADIO

Edward L. Crain, 145 Brunswick Ave. S.,
Golden Valley, Minn. 55427

Filed July 29, 1968, Ser. No. 12,936

Term of patent 14 years

Int. Cl. D8—03

U.S. Cl. D54—1

FIG. 1

FIG. 2

FIG. 3

FIG. 4

FIG. 5

FIG. 1 is a front elevational view of a holder for a portable radio, showing my new design.

FIG. 2 is a perspective sketch on a reduced scale.

FIG. 3 is a rear elevational view.

FIG. 4 is a side elevational view.

FIG. 5 is a top plan view thereof.

The broken lines are for illustrative purposes only.

I claim:

The ornamental design for a holder for a portable radio, as shown and described.
